Patented Mar. 22, 1960

187,500

HANDLE FOR BOTTLE-LIKE CONTAINERS

Webb C. Jennings, Rocky River, Ira T. Swartwood, Bay Village, and Rudolph A. Sampson, Cleveland, Ohio

Application June 4, 1959, Serial No. 56,217

Term of patent 14 years

(Cl. D58—26)

Fig. 1

Fig. 2

Fig. 3

Fig. 4

Fig. 1 is a side elevation of a handle for bottle-like containers and embodying our new design;

The broken line portions shown in Fig. 1 of the drawing are for illustrative purposes only.

Fig. 2 is an end view of the handle as viewed from one side thereof;

Fig. 3 is a bottom plan view of the handle; and

Fig. 4 is a top plan view of the handle.

We claim:

The ornamental design for a handle for bottle-like containers, substantially as shown and described.
